S. J. HOFF

KEYHOLE GUARD

Filed March 28, 1922

INVENTOR
S. J. Hoff
BY *J. Ledermann*
ATTORNEY

UNITED STATES PATENT OFFICE.

SIGURD JAHR HOFF, OF NEW YORK, N. Y.

KEYHOLE GUARD.

Application filed March 28, 1922. Serial No. 547,444.

To all whom it may concern:

Be it known that I, SIGURD JAHR HOFF, a citizen of the United States, residing at New York, in the county of New York and 5 State of New York, have invented certain new and useful Improvements in Keyhole Guards, of which the following is a specification.

This invention relates to locks and has 10 particular reference to a means insertable in the keyhole of a lock, the main object being a lock which will safeguard the same from being picked or otherwise tampered with.

Another object is to design the device in 15 such manner as to be proof against being broken off or jimmied out of the key hole, as is possible with the present day type of this class.

These and other objects will become apparent in the description below in which characters of reference refer to the like-named parts in the drawing.

Referring briefly to the drawing, Figure 1 is a sectional elevational view of a portion of a door showing my safety lock in the locked position in a keyhole.

Figure 2 illustrates a modified form of a safety lock.

Figure 3 is a front elevational view of the 30 preferred form in the unlocked position.

Figure 4 is a side elevational view of the same.

Describing the drawing more in detail, the numeral 1 indicates a door panel having 35 a conventional type of knob handle 2 and a door plate 3 secured thereto in the usual manner, on the inside of the door.

The modified form of safety lock illustrated in Figure 2 essentially comprises a 40 pair of spaced parallel bars 4 joined to each by a half bend 5. The free ends of the bars 4 are bent into outwardly projecting portions 6.

The preferred form of lock shown in the 45 remaining views is of an outline similar to the modified form, having a pair of spaced parallel bar members 7 joined at one end by a half bend 8. Each of said bars 7 slidably receive a tubular shell 9 having a longitudinal slot 10 which engages a fixed pin 11 located on each of the bars 7.

The free ends of shell 9 are provided with recesses 12 which receive a locking dog 13, the latter being pivoted by the pin 14. These

dogs are rotatable thru two quadrants, corresponding to the locked or released position. The dog secured to the upper bar, as illustrated in Figure 3 is in the released position while the dog on the lower bar is shown locked.

Bars 7 are provided with detents 15 on the adjacent sides near member 8 and are adapted to register with cutout portions 16 of the tubular shells 9 when the latter is in the position shown in Figure 1. Obviously 65 the yoke 17 of the padlock 18 will engage both the bars 7 and the shells 9 and retain the same in fixed relation to each other.

In use the safety lock is inserted in the keyhole of a lock, bend 8 entering first, and 70 pushed inward the locking dogs being rotated to the position shown in Figure 1. Bar members 7 are then slid into the shells until the detents 15 register with 16 after which a padlock yoke 17 can be inserted 75 through the detents thus securely locking the bar 7 within the shells. The dogs 13 contact with the ends of bars 7 when the latter is in locked position and prevent the rotation of the said dogs to the unlocked or re-released position.

As illustrated in Figure 1 the door panel 1 has a recess 19 formed therein on the outside surface of the door so that the dogs 13 will not project beyond the door surface and 85 permit the breaking off or snapping of the same by a marauder.

In opening the lock the padlock is removed and the bars 7 are extended, by pulling outwardly, permitting the dogs to be 90 urged into alignment with the bars 7. Further pull on the bend 8 will entirely withdraw the safety lock from the keyhole without the necessity of opening the door to do so.

I claim:—

1. A lock of the class described comprising a pair of rigid parallel bars, slotted tubular members slidable on said bars, locking dogs pivoted at the ends of said tubular members, and adapted to be locked in extended position and means for locking the said dogs in locked position.

2. The combination with a lock insertable in a key hole and a padlock, a pair of spaced parallel bars connected at one end, tubular members slidable on the said bars, and having recesses at the free ends, locking dogs

pivottally mounted in said recesses, ends of said locking bars adapted to abut the longitudinal edges of the locking dogs when the latter are aligned with each other, said 5 tubular members and bars having detents on the adjacent surfaces thereof, the detents of the outer member adapted to register with

the detents of its corresponding bar when in locked position and a padlock engaging said detents and retaining the said dogs in 10 locked position.

In witness whereof I affix my signature.

SIGURD JAHR HOFF.
